[57] **CLAIM**

The ornamental design for outdoor landscape lighting
fixture, as shown and described.

DESCRIPTION

FIG. 1 is a perspective view of an outdoor landscape
lighting fixture, showing one embodiment of our new
design;

FIG. 2 is a side elevational view thereof, each other side
elevational view being identical;

FIG. 3 is a top plan view thereof;

FIG. 4 is a bottom plan view thereof;

FIG. 5 is another perspective view of an outdoor land-
scape lighting fixture, showing a second embodiment of
our new design;

FIG. 6 is a side elevational view thereof, each other side
elevational view being identical;

FIG. 7 is a top plan view thereof;

FIG. 8 is a bottom plan view thereof;

FIG. 9 is another perspective view of an outdoor land-
scape lighting fixture, showing a third embodiment of
our new design;

FIG. 10 is a side elevational view thereof, each other side
elevational view being identical;

FIG. 11 is a top plan view thereof;

FIG. 12 is a bottom plan view thereof;

FIG. 13 is a perspective view of an outdoor landscape
lighting fixture, showing a fourth embodiment of our
new design;

FIG. 14 is a side elevational view thereof, each other side
elevational view being identical;

FIG. 15 is a top plan view thereof; and,

FIG. 16 is a bottom plan view thereof.
